(57) **CLAIM**

The ornamental design for rear combination lamps for automobile body, as shown and described.

DESCRIPTION

FIG. 1 is a perspective view of a first embodiment showing rear combination lamps for automobile body of the new design installed on an automobile body;

FIG. 2 is a front view thereof;

FIG. 3 is a left side view thereof;

FIG. 4 is a right side view thereof;

FIG. 5 is a top view thereof;

FIG. 6 is an enlarged view of the rear combination lamps for automobile body shown in FIG. 3 without illustrating a transparent cover thereon;

FIG. 7 is an enlarged view of the rear combination lamps for automobile body shown in FIG. 4 without illustrating a transparent cover thereon; and,

FIG. 8 is a perspective view of a second embodiment showing rear combination lamps for automobile body of the new design installed on an automobile body.

The broken line showing the automobile body is only for illustrative purposes and forms no part of the claimed design.
